UNITED STATES PATENT OFFICE.

BENJAMIN F. WEYMER, OF CEDAR RAPIDS, IOWA.

GATE.

Application filed July 13, 1922. Serial No. 574,656.

To all whom it may concern:

Be it known that I, BENJAMIN F. WEYMER, a citizen of the United States, residing at Cedar Rapids, in the county of Linn and 5 State of Iowa, have invented certain new and useful Improvements in Gates; and I do declare the following to be a full, clear, and exact description of the invention, such as will enable others skilled in the art to 10 which it appertains to make and use the same.

This invention relates broadly to an improved gate, but has more specific reference to a gate which is especially designed to accommodate a sign or panel used for advertising purposes.

The object of the invention is to simply arrange a frame on one side of the gate, wherein the vertical end bars of this frame 20 are positioned directly opposite the intermediate reinforcing bars on the opposite side of the gate, together with a removable panel or sign fitted into the frame, this panel being such in construction that it assists in 25 reinforcing the frame members and details of the gate.

In the accompanying drawing forming a part of this specification and in which like numerals are employed to designate like 30 parts throughout the same:

Figure 1 is a side elevation of a gate constructed in accordance with this invention and equipped with a removable advertising sign.

Figure 2 is a horizontal section taken on the line 2—2 of Fig. 1.

Figures 3 and 4 are transverse or vertical sections taken on the lines 3—3 and 4—4 respectively of Fig. 1.

Figure 5 is a detail perspective view of the removable sign.

In the drawing, the reference character A designates a plurality of horizontally disposed vertically spaced pieces which are rigidly connected together by opposite end and intermediate bars B and C respectively. The intermediate reinforcing bars referred to are only on one side of the gate and as usual, a diagonal brace D is associated therewith.

50 In practice, a top board E will also be employed and this board by preference is com-

paratively wide to insure rigidity of construction and to protect the other details in the gate against the elements to some extent.

Referring now to the opposite or front 55 side of the gate, it will be seen that a rectangular frame is secured to the pieces A, and this frame is composed of horizontal upper and lower strips 1 arranged between vertical end bars 2. It is to be noted that 60 the last named bars are positioned opposite the aforesaid reinforcing bars D, are secured in place by the same fastenings, and function in the same manner on this side of the gate. It is obvious from the foregoing description and from the drawings that a removable sign or panel generally designated by the numeral 3 is intended to be inserted into this frame and although this sign could be of some other construction, it is preferably formed from a sheet of metal 4 having 65 its edges directed outwardly at right angles to form flanges 5 which are strengthened somewhat by means of a supplemental frame bearing against the outer sides of the plate 70 and engaging the inner faces of the flanges. This frame is preferably constructed of strips of molding 6 to render the panel ornamental in appearance. The frame in addition to ornamenting the panel serves to reinforce 75 the flanges 5 and when the panel is in position in the first mentioned frame on the gate, these flanges in turn serve to reinforce the frame members 1 and 2.

In practice, the sheet metal plate of the 80 panel is painted and suitable advertising data together with a person's name is inscribed thereon. Hence, when the sign is in position in the frame on the front of the gate, it will serve as a unique method of advertising certain kinds of goods to passers-by.

By carefully considering the description in connection with the drawing, persons familiar with devices of this class will doubtless be able to obtain a clear understanding of the invention. Therefore, a more lengthy and detailed description is deemed unnecessary.

I claim:

100 A gate comprising a plurality of horizontal vertically spaced pieces connected to

gether by pairs of opposite vertically disposed intermediate and end bars, upper and lower horizontal supplemental strips arranged between the intermediate bars on one side of the gate, thus forming a rectangular frame on this side, a sheet of metal arranged in the frame and having its edges directed

at right angles to form flanges bearing against the frame members, and a second frame constructed of pieces of molding engaging the flanges to reinforce them. ¹⁰

In testimony whereof I have hereunto affixed my signature.

BENJAMIN F. WEYMER.
